UNITED STATES PATENT OFFICE.

JOSEPH TORANGO, OF PORTLAND, OREGON.

BOX.

973,321.

Specification of Letters Patent. Patented Oct. 18, 1910.

Application filed October 2, 1909. Serial No. 520,720.

To all whom it may concern:

Be it known that I, JOSEPH TORANGO, a citizen of the United States of America, and a resident of Portland, county of Multnomah, State of Oregon, have invented certain new and useful Improvements in Boxes, of which the following is a full and clear specification, reference being had to the accompanying drawings, in which—

10 Figure 1 is a perspective view of the improved box; Fig. 2 a vertical longitudinal section thereof on the line 2—2 of Fig. 4; Fig. 3 a horizontal section on the line 3—3 of Fig. 2; Fig. 4 a transverse vertical section on the line 4—4 of Fig. 2; and Figs. 5, 6, and 7 detail views described in the course of this specification.

15 The object of this invention is to provide a very strong and durable box for use in handling various articles of merchandise, it being especially intended and adapted for use as a substitute for the straw-board boxes and willow baskets now generally employed by bakers and others for delivering bread 20 and other merchandise.

25 Referring to the drawings by reference-characters *a* designates four corner posts, to which the bottom and vertical walls are fastened. The bottom of the box consists of a 30 series of longitudinal runner boards *b* to which are nailed the transverse slats *c* composing the bottom proper of the box, these slats being arranged in pairs and fastened one upon the other by rivets *d*, these rivets 35 passing through both thicknesses of the slats and through intermediate thin metallic straps *e* running longitudinally the full length of the bottom and carried up through the end walls in the manner hereinafter set 40 forth. The bottom is further braced by inside battens or strips *f* nailed down upon the slats *c* and through the runners *b*.

45 The two ends walls of the box are constructed alike, each consisting of a transverse bottom rail *g* and a transverse top rail *h* and intermediate slats *i* each constructed of two layers fastened together by rivets *j* in the same manner as the slats of the bottom. The rails *h* and *g* and the slats *i* are 50 of course fastened rigidly to the corner posts. The metallic straps *e* after they emerge from between the slats composing the bottom are bent downwardly around the lower edges of the rails *g* and upwardly 55 upon the outer faces thereof and thence upwardly between the pairs of slats *i*, their

upper extremities terminating in rabbets formed in the inner lower edges of the top rails *h*. The extremities lying in these rabbets are clamped in place and completely 60 covered and protected by filling slats *k*, which fit the rabbets and are nailed rigidly to the rails *h*. By this manner of constructing the bottom and the end walls of the pairs of slats and of tying them all together 65 by metallic straps extending the full length of the bottom and up through the slats composing the end walls a very rigid well-braced structure is obtained. A feature of importance is the manner of carrying up 70 the end portions of the metallic straps and embedding their extremities, so to speak, in the top rails of the end walls.

75 The side walls are constructed substantially like the end walls, being each composed of a bottom rail *l*, a top rail *m* and intermediate slats *n* arranged in pairs and fastened together by rivets *o*. These rails and slats are all tied together by thin metallic straps *p* which are clamped between 80 the slats *n* and have their extremities clamped in rabbets in the inner faces of the rails *l* and *m* by means of filling-slats *q*, similar to the filling-slats *k*. In this manner each side wall is a rigid structure, all its 85 rails and slats being tied together by the metallic straps, and the extremities of these straps being embedded in the top and bottom rails. These side walls are nailed to the corner posts and to the bottom. 90

95 A suitable cover *r* hinged to one of the side walls is employed and in connection therewith a suitable latching device *s* to hold the cover closed is used. At each corner of the box suitable thin metallic corner straps *p* are employed to fasten the walls together and thus strengthen and brace the box. For the purposes of clear illustration there is a space shown between the pairs of slats in Figs. 3 and 4 but it will be understood that in practice the metallic straps *e* and *p* shall be sufficiently thin to permit the companion slats to become closely into contact throughout their length when they are riveted together, this close contact being permitted by the embedding of the metallic straps in the adjacent surfaces of the slats, as shown in detail in Figs. 6 and 7. 100

105 Having thus fully described my invention, what I claim as new, and desire to secure by Letters Patent, is:—

A box structure consisting of inner corner

posts, a bottom attached thereto, end walls attached to the bottom and to the corner posts, side walls attached to the bottom and corner posts and each consisting of a top rail rabbeded along its inner face, a bottom rail similarly rabbeded, intermediate slats arranged in pairs, vertical metallic straps lying between the pairs of slats and having extremities lying in said rabbets, rivets passing through the pairs of slats and the intermediate metallic straps, and filling pieces or

slats fastened in said rabbets and inclosing and sealing the extremities of the metallic straps.

In testimony whereof I hereunto affix my 15
signature in the presence of two witnesses
this 27th day of September 1909.

JOSEPH TORANGO.
